UNITED STATES PATENT OFFICE

120,903

DESIGN FOR A LIGHT TRANSMITTING GLOBE

Albert L. Arenberg, Highland Park, Ill., assignor to Patent License Corporation, Chicago, Ill., a corporation of Illinois

Application April 5, 1939, Serial No. 84,051

Term of patent 14 years

To all whom it may concern:

Be it known that I, Albert L. Arenberg, a citizen of the United States, residing at Highland Park, in the county of Lake and State of Illinois, have invented a new, original, and ornamental Design for a Light Transmitting Globe, of which the following is a specification, reference being had to the accompanying drawing, forming a part thereof.

In the drawing:

Fig. 1 is a perspective view of the light transmitting globe, showing my new design; and

Fig. 2 is a side view of the same.

The surface of the globe which is shown in the drawing as stippled is light diffusing, while the relatively small surface which is shown without any stippling is clear.

I claim:

The ornamental design for a light transmitting globe, substantially as shown and described.

ALBERT L. ARENBERG.
